UNITED STATES PATENT OFFICE

161,768

BUILDING

Frank R. Kollmansperger, Chattanooga, Tenn.

Application May 10, 1950, Serial No. 9,842

Term of patent 14 years

(Cl. D13—1)

To all whom it may concern:

Be it known that I, Frank R. Kollmansperger, a citizen of the United States, residing at Chattanooga, in the county of Hamilton and State of Tennessee, have invented a new, original, and ornamental Design for a Building, of which the following is a specification, reference being had to the accompanying drawing, forming part thereof.

Figure 1 is a front perspective view of a building, showing my new design;

Figure 2 is a front elevational view thereof,

Figure 3 is a rear elevational view of the same;

Figure 4 is a side elevational view, showing the side not illustrated in Figure 1; and

Figure 5 is a top plan view.

I claim:

The ornamental design for a building, as shown.
FRANK R. KOLLMANSPERGER.
